A. E. LOEWY
CONTROLLER ACTUATION

Filed June 24, 1926

By

Inventor:
Aaron E. Loewy,
Hotchkissdale
Attorney.

Patented Oct. 9, 1928.

UNITED STATES PATENT OFFICE.

AARON E. LOEWY, OF PHILADELPHIA, PENNSYLVANIA, ASSIGNOR TO LIBERMAN
MANUFACTURING COMPANY, A CORPORATION OF DELAWARE.

CONTROLLER ACTUATION.

Application filed June 24, 1926. Serial No. 118,181.

The invention relates to controller actuation. The object is to provide improved means for maintaining an operative relationship between the control of the power and 5 the position of the machine elements at starting.

The invention is especially applicable to the control of full-fashioned hosiery knitting machines, such as described in my pending 10 application, Serial No. 727,858, filed July 24, 1924. In the machine described in said application a horizontal rod is provided which extends across the machine and is adapted 15 to be shifted by the operator to actuate a motor switch or other suitable control for starting the machine. A pivoted lever is arranged in operative relationship with said shift rod and also with elements of the knitting machine, so that when the shift rod is moved to 20 start the motor, the lever is also actuated to move the elements of the knitting machine into initial or starting position, and when the machine has performed a predetermined operation, as for example, has knitted a pre- 25 determined number of courses, an element of the machine will communicate movement through said lever to said shift rod to stop the motor.

In accordance with the present invention 30 I provide a rock shaft in place of the shift rod, as being much easier to operate. The operative relationship between the lever and shaft being secured for example by a cam on the rock shaft and a cooperating roller on the lever. In other respects the principle of operation is substantially the same.

Referring to the drawings, which illustrate merely by way of example suitable means for effecting the invention:—

Fig. 1 is a view in perspective.

Fig. 2 is a front elevation.

Fig. 3 is a side elevation.

Similar numerals refer to similar parts throughout the several views.

The rock shaft 5 occupies about the same 45 position on the machine, as the shift rod in my said application. It is provided with a suitable controlling arm 4, for the controller device 6. The lever 7 which is mounted on 50 a suitable fulcrum or pivot 8 engages at its lower end with a reciprocating element 9 which is operated in one direction to set the machine elements in initial or starting position, when the machine is started, and is operated in the other direction to move the lever 55

7 to stop the machine as hereinafter described. At the upper end of lever 7 is secured an adjustable piece or member 10 provided with a roller 11 preferably on ball bearings.

On the rock shaft 5 is adjustably secured 60 by means of the set-screw 12 a cam element 13. This cam element has a lip or projection 14, provided with a roller engaging margin 15 which is in the form of a spiral segment adapted to follow the roller as the shaft is 65 rocked.

The adjustment of fulcrum 8 with respect to lever 7 is secured by the following means.

A block 16 is swivelled on the pivot 8 secured to arm 17. A channelled clamp plate 70 18 receives the lever 7 and clamps the same to swivel block 16 by means of clamp screws 19.

By relieving the tension of screws 19 the swivel block 16 may be raised or lowered on the lever 7 and then clamped in desired position by adjustment. Thus the fulcrum 8 of lever 7 may be changed as required. In order that the upper and lower ends of lever 7 may remain unchanged, when the swivel block 16 is adjusted, the arm 17 is correspondingly adjusted. For this purpose the arm 17 is 75 slidably mounted on the channel of stationary bracket 20 and is held in position of adjustment by the clamp bolt 21 passing through the vertical slot 22 in said bracket 20. The 80 adjustment of fulcrum 8 with respect to lever 7 is desirable in order to secure the desired relative throw of the upper and lower ends of lever 7.

The channelled member 10 is also adjustably secured on the upper end of lever 7 by means of the clamp bolt 23 in slot 24, in order to maintain the desired relationship between roller 11 and the engaging cam face 15.

In operation, when the parts are, for example, in position shown in Fig. 1, and the operator by means of the usual hand grip, gives the rock shaft a partial turn in clockwise direction, the cam 13, engaging roller 11, causes the upper end of lever 7 to move to the 90 right and the lower end to move to left, thereby actuating slide member 9 to the left to set the machine elements in the starting position; at the same time the controller arm 4 is operated to start the motor. When the slide member 9 is automatically moved to the right, back to position shown in Fig. 1, after the predetermined operation of the machine, as described in my pending application, Serial No. 727,858, the lever 7 is operated so that 100 105 110

roller 11 engaging cam 13 causes a partial turn of rock shaft 5 to actuate the controller to stop the motor or otherwise shut off the power and stop the machine.

5 What I claim is:—

In a controlling mechanism, the combination of a pivoted lever, an element shifting

mechanism associated with one end thereof and power controlling mechanism associated with the other end thereof including a rock shaft, a spiral cam adjustably mounted thereon, and a cooperating roller adjustably mounted near the end of the pivoted lever. 10

AARON E. LOEWY.
